SAMUEL J. SHARP, OF WHEELING, WEST VIRGINIA, ASSIGNOR TO J. L. STIFEL & SONS,
OF WHEELING, WEST VIRGINIA, A FIRM.

JOURNAL-BEARING.

1,358,588.

Specification of Letters Patent.

Patented Nov. 9, 1920.

Application filed February 14, 1920. Serial No. 358,703.

To all whom it may concern:

Be it known that I, SAMUEL J. SHARP, a citizen of the United States of America, and resident of Wheeling, county of Ohio, and State of West Virginia, have invented certain new and useful Improvements in Journal-Bearings, of which the following is a specification.

This invention relates broadly to journal 10 bearings, and more particularly to a bearing of a self-lubricating type.

The chief object of the invention is to provide an efficient self-lubricating bearing for the necks or spindles of rolls of the general character employed in the open soaping and washing machines of textile plants and print works.

A further object is to provide a simple, durable and comparatively inexpensive 20 journal bearing structure which embodies means whereby the bearing is at all times kept adequately lubricated, which is extremely economical in the use of lubricating oil, which effectually guards against loss 25 of the lubricant through leakage, and which prevents the oil from draining from the bearing either into contact with the roll or into the water of the soaping machine.

With these and other important objects 30 in view, the invention resides in the features of construction, arrangement of parts and combinations of elements which will herein-after be fully described, reference being had to the accompanying drawings, in which—

35 Figure 1 is a side elevation of the invention illustrating the application thereof;

Fig. 2 is a central longitudinal section of the invention; and—

40 Fig. 3 is a view of the same partly in inner end elevation and partly in transverse section.

Referring to said drawings, in which like designating characters distinguish like parts throughout the several views—

45 1 indicates the body of a bearing support having a base 2, preferably integral therewith, for mounting in a suitable position, as upon a side 3 of the frame of an open soaping machine of the type commonly employed in textile plants and print works. Formed in said body 1 is a chamber or reservoir 4 for a lubricant. Rising above the reservoir at opposite sides are lateral walls 5, integral with said body 1, which 55 have their inner faces inwardly and down-

wardly inclined from their upper edges toward the top of the reservoir and terminating outward of, or being outwardly offset slightly at their lower edges with respect to, the upper edges of the adjacent interior 60 walls of the reservoir, whereby are formed internal shoulders 6. Removably seated upon said shoulders 6 are the lateral edges of the under side of a pillow block 7 which has therein a longitudinal channel 8 adapted 65 for the reception of the spindle or journal 9 of a shaft or roll, as the roll 10 of a soaping machine. The under side of said block is shouldered at its ends and lateral edges to seat more or less snugly within 70 the upper part of the reservoir for preventing relative shifting movement of said block.

Extending upward through the bearing block 7 at an approximate tangent to the 75 channel 8 thereof and opening into the latter at or slightly above the plane of the axis of the journal 9 when the latter is seated in said channel is a bore or passage 11 in which is received the body portion of a 80 suitable wick 12 which has its lower end depending within the reservoir and its upper end protruding slightly from the upper end of said passage so as to contact with the journal 9.

As is obvious, the wick 12, through capillary action, conducts lubricant from the reservoir and deposits the same upon the journal with which its upper end is disposed in wiping contact. Excess lubricant 85 conducted as aforesaid into the channel 8 of the pillow block 7 drains back into the reservoir, the outer end of said block having therein a drain channel 13 in open communication at its upper end with said channel 8. A similar drain channel may also be employed at the inner end of said block, but I prefer that the inner end face of said block shall be slightly inclined in a downward and inward direction, as is best shown 100 at 14 in Fig. 2. Obviously, oil draining from the inner end of the channel 8 will follow the inclined face 14 and return to the reservoir. It will be noted that there can be absolutely no leakage or waste of lubricant and, consequently, that not only can no oil find access from the bearing to the water of the soaping machine, but also a condition of muzziness in the bearing is avoided.

A suitable cover, as 15, is provided for preventing dust, lint and the like from settling and collecting upon the lubricated surfaces of the device.

5 What is claimed is—

1. A self-lubricating journal bearing comprising a pillow block of approximately rectangular form in cross section and channeled longitudinally for the reception of 10 a journal, said block having a bore extending upward therethrough and opening into the channel thereof adjacent to the level of the axial line of the latter, a support disposed in underlying relation to said pillow 15 block and having a lubricant reservoir therein, said block being removably seated upon said support and having its underside extending within the top of said reservoir for preventing relative shifting movement, the ends of said block being shaped 20 to permit drainage of lubricant from said channel to the reservoir, and a wick disposed in the bore of said block, said wick having its lower end depending within said

reservoir and its upper end protruding into 25 said channel.

2. A self-lubricating journal bearing comprising a pillow block channeled for the reception of a journal, said block having a bore extending upward therethrough and 30 opening into the channel thereof, a support upon which said pillow block is removably seated, said support having a lubricant reservoir therein beneath said block, the ends of said block being shaped to permit drainage of lubricant thereover from 35 said channel to the reservoir, and a wick disposed in the bore of said block, said wick having its lower end depending within said reservoir and its upper end protruding into 40 said channel.

In testimony whereof I affix my signature in presence of two subscribing witnesses.

SAMUEL J. SHARP,

Witnesses:
